CLAIM

The ornamental design for a loudspeaker, as shown and described.

DESCRIPTION

FIG. 1 is a top perspective view of a loudspeaker showing our new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The evenly spaced broken lines in the figures illustrate portions of the loudspeaker that form no part of the claimed design. The dot-dash broken lines in the figures represent boundaries of the claimed design and form no part of the claimed design. The shading is provided merely to represent contours of the design and does not connote the character of
